(57) **CLAIM**

The ornamental design for a skid mounted garbage and waste facility, as shown and described.

DESCRIPTION

FIG. 1 is a front perspective view of the embodiment of the skid mounted garbage and waste facility;

FIG. 2 is a rear perspective view of the skid mounted garbage and waste facility;

FIG. 3 is a front view of the skid mounted garbage and waste facility;

FIG. 4 is a left side view of the skid mounted garbage and waste facility;

FIG. 5 is a rear view of the skid mounted garbage and waste facility;

FIG. 6 is a right side view of the skid mounted garbage and waste facility;

FIG. 7 is a top view of the skid mounted garbage and waste facility;

FIG. 8 is a bottom view of the skid mounted garbage and waste facility; and,

FIG. 9 is a sectioned inside top view of the skid mounted garbage and waste facility taken along the line 1-1 in FIG. 3.
